BRASSIÈRE

Clarissa M. Cooney, St. Albans, and Lillian Claire Matthews, Glen Cove, N. Y.

Application July 30, 1952, Serial No. 301,738

3 Claims. (Cl. 2—42)

This invention relates to bust-supporting garments or brassières, and is more particularly concerned with a garment of this character which has structural features which adapt it more effectively to support and retain the bust of the wearer.

Conventional brassières generally provide adequate vertical support for the bust but provide little or no lateral support, and as a result, when these brassières are worn they have a tendency to decrease the apparent natural size of the bust. There have been various proposals, therefore, to employ padding, inflatable units, and other artificial means to compensate for this lack of lateral support and to increase the apparent size of the bust. Such expedients, however, are only partially effective and suffer from numerous disadvantages which limit their usefulness.

It is the principal object of the present invention to provide a brassière of improved construction which provides both vertical and lateral support for the bust of the wearer.

It is a further object of the invention to provide a brassière of the character indicated in which the degree of lateral support is readily adjustable to any desired extent.

It is a further object of the invention to provide a brassière having adjustable means for controlling the extent of support applied to the bust and for controlling the apparent contour of the bust.

It is another object of the invention to provide a brassière which is adapted to enhance and augment the apparent natural size and form of the bust of the wearer without recourse to the use of padding, inflatable devices, and like wholly artificial means.

In accordance with the invention, there is provided a brassière having a pair of breast-receiving pockets constructed to cover only a limited extent of the upper portion of the breasts of the wearer, shoulder straps exerting an upward pull upon the outer sides of the pockets, and adjustable lateral support-providing tie straps connected at one end to the shoulder straps at a point spaced from the upper ends of the pockets and having free ends adapted to be received in apertures or the like positioned at the center of the front portion of the brassière closely-adjacent the juncture of the pockets, the free ends of the tie straps being adapted to be tied together to any desired extent.

It is a feature of the brassière of the invention that the tie straps can be drawn up and tied to any desired extent to provide any desired degree of lateral support for the bust.

It is a further feature of the brassière of the invention that the lateral supporting means incorporated in it are effective to increase the apparent size of the bust of the wearer in a comfortable, natural manner and make unnecessary the provision of padding or other bulk-providing expedients.

Other objects and features of the invention will be readily apparent from the following detailed descrip-

2

tion of an illustrative embodiment of a brassière constructed in accordance with the invention, and from the accompanying drawing, wherein,

Fig. 1 is a perspective view of a brassière embodying features of the present invention, showing the brassière in loose, unsecured position; and

Fig. 2 is a similar view of the same brassière, showing it in applied position with the tie straps tightened and tied to provide the desired lateral support for the bust.

Referring to the drawing, the reference numeral 10 designates generally the brassière illustrated, which is formed with two breast-receiving portions or pockets 12 and 13, joined centrally of the brassière at 15. The lower portions of the pockets 12 and 13 are secured to a non-extensible diaphragm band portion 17 which extends across the front of the brassière 10 and is adapted to firmly engage the body of the wearer to prevent upward displacement of the brassière. Extending rearwardly from the other sides of the pockets 12 and 13 are back-straps or extensions 19 and 20, respectively, which have at their free ends any convenient cooperating fastening means, as for example the hooks 21 and eyes 22 shown, for securing the brassière 10 around the body of the wearer. For insuring an accurate and comfortable fit, the extension 20 is provided at its end with an elastic strip 25 upon which the eyes 22 are mounted, and elastic inserts 27 and 28 are interposed between the ends of the extensions 19 and 20 and the sides of the pockets and the diaphragm band portion 17.

The breast pockets 12 and 13 are of substantially half-cup shape, being formed with darts 30 and 31 to provide the desired contour. In accordance with the invention, the pockets 12 and 13 have arcuate lower portions 33 and 34, respectively, which are adapted to engage and cover the lower half of the wearer's breasts, and upper portions 36 and 37, respectively, which are of substantially lesser height and are adapted to extend a relatively short distance over the upper portions of the breasts. At 38 and 39 are indicated the forwardmost portions or apices of the pockets 12 and 13, respectively, and thus the line of juncture of the lower arcuate portions and the upper portions of the pockets, which meet at 40 and 41 at the outer edges of pockets 12 and 13, respectively. As seen in the drawing, the apices of the pockets 12 and 13 are closely adjacent the substantially rectilinear upper edges 42 and 43 of the pockets with the result that the pockets 12 and 13 overlie only a very small extent of the upper portions of the wearer's breasts.

Shoulder straps 45 and 46 are connected, respectively, to back extensions 19 and 20, adjusting buckles 50 being provided for varying the effective length of the shoulder straps. In the embodiment illustrated, the buckles are secured to short extensions 51 and 52 which are connected to strap portions 54 and 55, secured in any convenient manner to the upper ends of the pockets 12 and 13, respectively adjacent their outer edges. The strap portions 54 and 55 may be integral with the extensions 51 and 52 or they may be separately secured thereto. At the point of juncture of the extensions and the strap portions 54 and 55, there are secured tie straps 57 and 58 which, as will be described, are adapted to be adjustably connected to the pockets 12 and 13 to exert a lateral supporting force upon them and thereby to create an effective lateral supporting action upon the bust of the wearer. While the point of attachment of the tie straps 57 and 58 to the shoulder straps may vary to some extent, advantageously the distance from the point of attachment to the center lines 40 and 41 of the pockets 12 and 13 is substantially equal to the distance between the center lines 40 and 41 and the diaphragm band 17.

For receiving the ends of the tie straps 57 and 58, the pockets 12 and 13 are provided with eye means which,

in the embodiment illustrated in the drawing, are apertures or eyelets 60 and 61 formed in pockets 12 and 13, respectively. The eyelets 60 and 61 are reinforced with buttonhole stitching, grommets, or the like. As shown in the drawing, the eye means are two in number and are positioned in each pocket closely adjacent the line of juncture of the pockets and closely adjacent the upper edges 42 and 43 of the pockets.

When the brassière 10 is worn, the shoulder straps 45 and 46 are slipped over the shoulders of the wearer and the hooks and eyes 21, 22 engaged in the usual manner. The shoulder straps are adjusted to the most comfortable position for the wearer. It is a feature of the brassière of the invention that the tie straps 57 and 58 are operable independently of the shoulder straps so that the desired tension on the tie straps, and thus the desired lateral supporting force, may be realized regardless of the tension on the shoulder straps. The tie straps 57 and 58 are passed through the eye means in the pocket on the opposite side of the brassière and the tie straps are then drawn to any desired tension and tied together. Thus, the tie strap 57 is passed from the back to the front through the eyelet 61 and the tie strap 58 is passed from the back to the front through the eyelet 60. The tie straps are then drawn up to apply lateral supporting force upon the bust and are tied together, as by a bow 62.

It will be observed that when the tie straps 57 and 58 are drawn up, they form triangles with the shoulder strap portions 54 and 55 and the upper edges 42 and 43 of the breast pockets, the lower ends of the shoulder straps 45 and 46 being drawn toward the center of the brassière 10 in this position effects a lateral thrust upon the bust of the wearer and not only effectively supports the bust but augments its apparent natural size and contour.

While the invention has been described and illustrated by reference to a preferred embodiment thereof, it will be readily apparent that various changes and modifications may be made in this embodiment without departing from the scope of the invention as defined in the appended claims, and it is intended that all matter contained in the foregoing description and in the drawing shall be interpreted as illustrative only and not as limitative upon the invention.

We claim:

1. In a brassière, an inextensible front band portion, a pair of breast pockets extending upwardly from said band portion and having a point of juncture substantially at the vertical median line of said band portion, said pockets being formed from a lower semi-cup-shaped portion adapted to cover the lower half of the wearer's breasts and an upper partly cup-shaped portion of substantially lesser height adapted to extend over only a portion of the upper half of the breasts, shoulder straps connected to the pockets adjacent the outer ends thereof, a tie strap connected to each shoulder strap at a point spaced upwardly from the upper edge of each pocket, the tie straps being connected to the brassière only at the point of attachment to the shoulder straps and having free ends, and spaced-apart eye means adjacent the point of juncture of the pockets for receiving the free ends of said tie straps, each of the tie straps having a length substantially greater than the distance from said point of attachment to said eye means, whereby said free

ends may be passed through said eye means and adjustably interconnected for adjusting the lateral supporting forces on the bust of the wearer independently of the tension on the shoulder straps.

5 2. In a brassière, an inextensible front band portion, a pair of breast pockets extending upwardly from said band portion and having a point of juncture substantially at the vertical median line of said band portion, said pockets being formed from a lower semi-cup-shaped portion adapted to cover the lower half of the wearer's breasts and an upper partly cup-shaped portion of substantially lesser height adapted to extend over only a portion of the upper half of the breasts, the apices of said pockets being closely adjacent the upper edges thereof, 10 shoulder straps connected to the pockets adjacent the outer ends thereof, a tie strap connected to each shoulder strap at a point spaced upwardly from the upper edge of each pocket, the tie straps being connected to the brassière only at the point of attachment to the shoulder straps and having free ends, and spaced-apart eye means adjacent the point of juncture of the pockets for receiving the free ends of said tie straps, each of the tie straps having a length substantially greater than the distance from said point of attachment to said eye means, whereby 15 said free ends may be passed through said eye means and adjustably interconnected for adjusting the lateral supporting forces on the bust of the wearer independently of the tension on the shoulder straps.

20 3. In a brassière, an inextensible front band portion, a pair of breast pockets extending upwardly from said band portion and having a point of juncture substantially at the vertical median line of said band portion, said pockets being formed from a lower semi-cup-shaped portion adapted to cover the lower half of the wearer's breasts and an upper partly cup-shaped portion of substantially 25 lesser height adapted to extend over only a portion of the upper half of the breasts, shoulder straps connected to the pockets adjacent the outer ends thereof, a tie strap connected to each shoulder strap at a point spaced upwardly from the upper edge of each pocket, the tie straps being connected to the brassière only at the point of attachment to the shoulder straps and having free ends, the distance between the juncture line of the upper and lower portions of said pockets and the point of attachment of said tie 30 straps to said shoulder straps being substantially equal to the distance between said juncture line and the upper end of said inextensible band, and spaced-apart eye means adjacent the point of juncture of the pockets for receiving the free ends of said tie straps, each of the tie straps having a length substantially greater than the distance from said point of attachment to said eye means, whereby said 35 free ends may be passed through said eye means and adjustably interconnected for adjusting the lateral supporting forces on the bust of the wearer independently of the tension on the shoulder straps.
